CLAIM

The ornamental design for a can-shaped helmet, as shown and described.

DESCRIPTION

FIG. 1 is a front top perspective view of the can-shaped helmet, showing my our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the can-shaped helmet that form no part of the claimed design.
